SLIDING GROOVE LOCK

James H. Arkus, New York, N. Y.

Application January 14, 1938, Serial No. 185,054

2 Claims. (Cl. 292—147)

This invention relates to locks for fastening devices for pocketbooks, handbags and the like, and has for its main object to provide a device of this character which will be extremely simple in construction, efficient and reliable in operation, and inexpensive to manufacture.

Another object of this invention is to provide a locking device of the type indicated in which a sliding member is provided in a channel or groove, in one of the two elements to be releasably secured together, said sliding member having a depending portion adapted to engage or disengage an appropriate part in the other one of said two elements when sliding in one or in the other direction, respectively, in a slot or recess provided in the bottom of said channel.

Other objects of this invention will be apparent as the specification of the same proceeds.

In the drawing, forming a part of this specification and accompanying the same:

Fig. 1 is a plan view of a pair of hinged frame members for a handbag, pocketbook, or the like, in a partly open position;

Fig. 2 is an end elevation of the device shown in Fig. 1;

Fig. 3 is a sectional detail on the line 3—3 of Fig. 1, the showing being on a larger scale than Figs. 1 and 2;

Figs. 4 and 5 are side and end elevations, respectively, of a sliding member used in my device; while

Figs. 6 and 7 are side elevation and plan view, respectively, of a flat spring therein; and

Fig. 8 is a fragmentary detail showing a slot provided in the bottom of a channel in my device.

Referring now to the drawing more in detail, by characters of reference, the numerals 10 and 11 indicate the two frame members of a pocketbook, handbag, or the like, being hingedly joined, as at 12, their construction and use being well known in this art. Each frame member 10 and 11 may be bent into a channel shape, having outer identical branches 10a and 11a over the inner branches 10 and 11, each frame member preferably being bent out of one piece of sheet material, the interconnecting transverse portions of the frame channels being indicated at 10b and 11b, respectively. This doubling of the frame members is not an essential part of my invention and is shown only as one form of my device, and the outer doubled frame branches are applied only for better manufacturing, for more rigid construction, for ornamental purposes, and to facilitate the application of the frame members on a handbag, pocketbook, or the like. The up-

per edge of the frame member 10 is terminated in a T shaped rail 13 with the enlarged head forming a rail 14 in which is provided a channel or groove 15.

A locking and catch or grip member 16 is arranged in a slideable manner in said groove 15, its lower base portion 17 substantially filling out the cross section of the groove 15 thereof, but being easily slideable therein, and its upper plate like shank 18 projecting from said groove 15, adapted to be used as a grip or catch for the operation of my lock. In the central portion of the rail 14, a slot 19 of limited length is provided in the bottom 20 of the groove 15, and substantially opposite to the left end of the slot 15 19 (as viewed in Figs. 1 and 8), an extension or nose 21 is arranged on the top of the frame member 11.

When my device is assembled, the sliding member 16 is arranged over the slot 19, and in the bottom part 17 of said sliding member, a recessed portion 22 is provided, into which is set a downwardly curved flat spring 23, having an extension or nose 24, substantially perpendicular to the curved surface thereof, as indicated in Figs. 2 to 7, and said nose 24 is projecting through the slot 19 in the bottom of the rail 14 and is slideable in said slot.

The use and operation of my device is as follows:

When it is desired to open the handbag, pocketbook, or the like, the sliding member 16 will be pushed to its rightward extreme position (as viewed in Fig. 1) and in this situation, there is no obstacle against swinging the frame members 10 and 11 away from one another on their pivots 12. When it is desired to fasten or lock the frame members together, they will be closed upon one another, swinging on the pivot 12, and then the sliding member 16 will be moved leftwardly, in the direction of arrow 25, up to the left limit of the slot 19, and in such a position the depending nose 24 on the spring 23 will engage and ride on the outer side 21a of the nose 21, on the frame member 11 and, in the final locking position of the sliding member 16, said nose 24 will entirely overlap the nose 21 and thereby lock the frame members together.

It will be obvious that when the sliding member 16 is moved reversely, to the opposite limit of slot 19, as has been mentioned hereinbefore, the two frame members will be released from one another, and it also will be obvious that for the successful operation of my device, the outer edge 21b of the nose 21 must be below the bot-

55

tom 20 of the rail 14 when the two frame members are closed on one another, and it must close on the frame member 10 in such a tight manner that the depending nose 24 may pass over it (Fig. 3).

For an easier and gradual locking operation and for a better locking action, the outer side 21a of said nose 21 may be made rightwardly pointed and inclined, as indicated in Fig. 1.

The assembly of the various parts of my sliding groove lock will be obvious to those versed in this art, I, however, desire to mention that the curved spring 23 may be inserted into the sliding member 16, with its depending nose 24 in the slot 19, in various manners. So, for instance, the depending member 24 may be equal or smaller in length than the height of the groove 15 and the spring may be forced into said groove 15 from one end thereof until it arrives over the slot 19, when the nose 24 may be allowed to drop into said slot and thereupon the sliding member 16 may be started from one end of the groove 15 and pushed towards the center until it will pass over the spring 23 and permit the same to snap into the recess 22 in the member 16. For the purpose of such operation, the forward and rearward ends, or possibly only one of them, of the sliding member 16, may be rounded, as indicated at 26.

Another method of inserting the spring 23 into the sliding member 16 with the depending nose 24 playing in the slot 19 may consist in forcing the spring 23 through the slot 19 from below, temporarily flattening the same into the plane of its nose 24, and thereafter allowing, or, with the use of a tool, forcing, the spring proper 23 to engage the widths of the groove 15 over the slot 19, while the nose 24 will remain in a depending position in said slot 19.

It also will be obvious that the plate or shank portion 18 of the sliding member 16 may be used as a base for ornaments, decorations, and to form a grip or catch for operating my lock, and that other forms of sliding members 16, rails 14, and depending noses 24, may be used in the combination of my invention, and, indeed, the spring 23 may entirely be omitted and the depending nose 24 formed directly as part of the sliding member 16.

It also will be obvious that other changes and variations may be resorted to in the details of construction and in the combinations of my device, and I want it to be understood that I reserve my rights to all such variations and changes

which are within the spirit of this specification and the scope of the claims hereunto appended.

One of such changes may consist in making my device, so to say, double acting, that is providing a second frame element 11 at the opposite side of frame element 10, making the rail 14 wider to overhang said second frame element 11, and providing a second slot 19 and a second depending nose 24 for said second element 11, as will be understood.

What I claim as new, is:

1. To releasably fasten together two elongated elements, normally in close parallelism with one another, a channel in one element, having a longitudinal slot in a wall thereof, a sliding member in said channel, a first nose, traveling with and secured to said sliding member and projecting therefrom through said slot, an upstanding second nose on the other one of said two elements, said first nose in its travel being adapted to engage said second nose and thereby secure the two elements to one another or to disengage the same and release said elements, a spring device in said sliding member, said spring slidably engaging a wall of said channel to steady the movement of said sliding member and to movably fix it in its various positions, said first nose being a part of said spring.

2. To releasably fasten together two elongated elements, normally in close parallelism with one another, a channel in one element, having a longitudinal slot in its bottom, a sliding member in said channel, a first nose traveling with and secured to said sliding member and depending therefrom through said slot, an upstanding second nose on the other one of said two elements, its upper edge being below the bottom of said channel when said elements are closed on one another, said first nose in its travel being adapted to engage said second nose and thereby secure the two elements to one another or to disengage the same and release said elements, said sliding member having a wider base portion to slidably but substantially fill out a part of said channel, a shank portion projecting over said base and through the mouth of said channel to provide a grip for said sliding member, said sliding member having a recess in its bottom, and a curved flat spring inserted into said recess, the lowest part of said spring engaging the bottom of said channel, and an extension on said spring substantially perpendicular to its curved surface to form said first mentioned nose.

JAMES H. ARKUS.
